UNITED STATES PATENT OFFICE.

VICTOR M. SUMMA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR END CONSTRUCTION.

1,109,604.

Specification of Letters Patent.

Patented Sept. 1, 1914.

Application filed July 3, 1912. Serial No. 707,639.

To all whom it may concern:

Be it known that I, VICTOR M. SUMMA, residing at St. Louis, Missouri, and being a citizen of the United States, have invented 5 certain new and useful Improvements in Car End Construction, of which the following is a full, clear, and exact description, such as will enable others skilled in the art to which it appertains to make and to use 10 the same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

In said drawings: Figure 1 is an end elevation of the body of a gondola car, certain 20 parts being omitted from one side thereof, and showing an end plate forming the physical embodiment of my invention. Fig. 2 is a side elevation of the end of the car shown adjacent the end disclosed in Fig. 1.

25 My invention relates to the end plates of railroad cars, and more particularly relates to a means for reinforcing and strengthening such an end plate.

While the invention will be described particularly with reference to the end plate of a gondola car, it is to be understood that the invention is not specifically limited to such a structure, and the novel features disclosed in this application may be applied with obvious mechanical changes and variations to the sides of cars and to different types of car.

The object of the invention is to eliminate the end braces now in general use, and to provide a single integral end plate so 40 stamped to form integral ribs and pockets, and flanged to form the necessary chords and attaching members.

A further object of the invention is to provide an end plate of a simple, inexpensive and readily formed construction, adapted to afford means for accommodating the grab rails, brake mast platforms and other fixtures from a relatively thin sheeting forming the load retaining wall. The end plate 45 may be formed in a press and, to facilitate pressing the metal, as well as to insure release of such metal from the dies employed, all of the perimetrical flanges formed thereon are caused to extend in the same direction 50 away from the body of the plate. The ob-

ject of this is two-fold. First, as above stated, and, secondly, because the plate with outstanding flanges; that is flanges projected away from or beyond the body portion of the car, may be riveted to the lapping side sheets of the body of the car by machine-driven rivets. A convenient apparatus for the purpose is a power-driven riveting machine suspended from a suitable trackway above the work, and which machine 60 may be raised or lowered by the operator engaged in setting the rivets, with minimum effort. If the flanges of the end plate lap the car body, the process of driving the securing rivets is more difficult and more expensive. When the horizontal flanges and the vertical flanges are being formed in the press, there is a tendency on the part of the metal to wrinkle, due to torsional stresses 70 set up in the metal. To offset such tendency 75 the transverse corrugations are formed in the sheet, thereby not only guarding against such wrinkling but also materially stiffening it when finished, and it is preferred that such corrugations extend across the major 80 portion of the end sheet. Near the corner portions there is an excessive tendency to wrinkle or bulge outwardly in pressing the metal, and to utilize this tendency the invention contemplates the formation of the 85 crescent-shaped protuberances 10, shown on the drawing, and utilize them as push pole pockets, thus dispensing with the customarily used separately formed push pole pockets. As the thrust in such pockets is 90 generally toward the middle portion of the car, the crescent-shaped pocket shown is sufficient for all practical purposes of service.

I attain the above outlined objects in general by stamping from the sheet forming the 95 end plate a plurality of ribs and pockets integral with the plate, and forming integral with the plate and outlining the same a continuous flange.

The invention further resides in the assemblage of the end plate above outlined with the usual car members, so as to form, in this instance, a gondola car of a simple, rigid construction and of a minimum number of parts.

In the several figures I have shown the spaced apart longitudinally extending lower side angles or sills A, in this instance shown to be angle-irons having a depending outer flange, supported on a horizontal flange of 110

which side sills and bridging the space between the same is the bottom or floor B. Fitting against each outer depending flange of the side sill A are the side girders C, the 5 upper edge of each of which is attached to the depending flange of the upper flanges D, which flanges are also shown to be in the form of angle-irons.

Resting upon the floor B, and positioned 10 between the side girders C at each end of the car, is the end plate E, which end plate and its attached parts more particularly form the subject-matter of this invention. The end plate E is shown to be a flat metallic 15 sheeting of the general rectangular shape usual with gondola cars, outlining which are outstanding flanges integral with the plate, the top flange 3 acting as a top chord for the plate and the bottom flange 4 af- 20 fording a bottom attaching flange, by means of which the end plate E is riveted, or otherwise fastened, to the floor or bottom trans-verse sill connecting members. This bottom flange 4 acting together with the floor B 25 affords means for connection with the de- pending draft sills F, lower brake mast bearing bracket G and end steps H, all of which members are riveted or otherwise se- cured by through bolts or rivets to the flange 30 4 and floor B.

The outturned side flanges 5 and 6 afford means by which the end plate is fastened to the side girders, and as shown in this in-stance, are fastened by means of the through 35 rivets 7, which not only afford means for fastening the end plate and side girder to-gether, but may also afford fastening means for one end of the grab-irons J. The end plate E is further braced in position on the 40 side girder C by means of the top gusset plates K, which bridge the corner between the side girder and end plate and are suit-ably fastened to the top flange 3 and the upper angle D.

45 In order to retain the load, a relatively thin metallic end plate is sufficient, but in order to withstand abnormal end shocks it has been found necessary to brace this end plate, which bracing has usually been ac- 50 complished by means of separate end brac- ings extending horizontally across the end plate. I attain the same brac- 55 ing with the minimum amount of material by pressing from the body of the plate E horizontally spaced apart corrugations or ribs 8, which project from the plate prefer- ably in the same direction as the flanges 3, 4, 5 and 6, and preferably extending from the plate a distance equal to the width of 60 said flanges. As shown in the illustration, ribs 8 are U-shape in cross section, but it is, of course, to be understood that a V or any other configuration may be used in order to attain the above outlined desideratum. 65 As shown in Fig. 1, these ribs terminate

within the bounding edge of the plate, so as to leave the flat space 9 between the ribs and the adjacent flanges. While these ribs have been shown to be two in number, it is to be understood that as many of these ribs may be used as is necessary to brace the particular form of car in which this form of plate may be used. In order to form lower push pole pockets, each lower corner of the plate is pressed into a project-ing semicircular ring 10, this pressing prefer-ably extending outwardly; that is, in the direction corresponding to the direction of the ribs 8 from the plane of the plate E. It will thus be seen that within a single integral plate there is formed reinforcing ribs or corrugations and push pole pockets, thereby eliminating the necessity of adding members to the end plate to form reinforce-ments and push pole pockets. An end plate 80 so formed affords means for the ready at- 85 tachment of car members, and, as shown, the grab-irons L may be riveted to the flat portion of the rear plate between the ribs 8, and any torsion in this flat portion, due to 90 a weight on the rings of the grab-iron, is materially resisted by the ribs 8, which ex- 95 tend in the same direction as the grab-irons. Further, by this construction of end plate, the brake mast platform M may be sup- 100 ported on outwardly extending brackets N, which brackets have vertically extending flanges O and P at opposite ends fastened by rivets Q to the flat portion of the plate E. The brake mast is herein shown as hav- 105 ing its lower end journaled in the brake mast bracket G, supported from the floor B and lower flange 4, and extending through the said platform M.

It will be noted that the brackets N sup- 110 porting the platform and mast straddle one of the ribs 8, and the downwardly inclined member S of the bracket N is in contact with, or in juxtaposition to, an outer edge of the rib 8, which construction has the ef- 115 fect of bracing the platform M and mast R to an end plate, which end plate although formed of thin metal has a resistance to buckling, due to its corrugations, equal to an end plate constructed of much thicker material.

I claim—

1. In a freight car, a single end plate having an integral outturning and outlining continuous flange affording means for at- 120 taching said end plate to adjacent car mem- bers, said plate having integral ribs within said outlining flange and reinforcing said end plate.
2. In a metal car, a pressed end plate 125 provided with a body portion and horizontally extending integral reinforcing corrugations and perimetrical flanges extending outwardly from the car, and side sheets extending beyond the body portion of the 130

end sheetlapping and being secured by direct rivet connection to said flange.

3. In a gondola car, an end plate provided with perimetrical flanges extending outwardly from the transverse portion of said plate, side wall plates lapping and secured directly to some of said flanges, and a floor lapping another of said flanges.

4. As an article of manufacture, a sheet metal end for a car pressed from a single sheet of metal and having vertical flanges

and push pole pockets formed therein near said flanges, and having transversely extending corrugations across the major portion of said sheet.

In witness whereof I have hereunto set my hand in the presence of two witnesses.

VICTOR M. SUMMA.
